Philip Sawyer, Miss Klemens,

UNITED STATES PATENT OFFICE.

KIRK H. WHITE, OF OSWEGO, NEW YORK, ASSIGNOR OF ONE-HALF TO MARSHALL S. ELY, OF NEW YORK, N. Y.

UNION SUIT.

1,147,349.

Specification of Letters Patent. Patented July 20, 1915.

Application filed February 4, 1914. Serial No. 816,410.

To all whom it may concern:

Be it known that I, KIRK H. WHITE, a citizen of the United States, residing at Oswego, county of Oswego, and State of New York, have invented certain new and useful Improvements in Union Suits, fully described and represented in the following specification and the accompanying drawings, forming a part of the same.

10 This invention has reference to improvements in union suits and is directed particularly to means for combining a union suit with a hose supporter.

15 The general object of this invention is the provision of an improved combined union suit and hose supporter, in which the hose supporter may be readily attached to a portion of the union suit and preferably with the garter adjustable to different positions at the point of attachment, so that the hose-engaging clasp may be caused to depend therefrom at different distances, and which shall be comfortable to wear, attractive in appearance, and convenient for the 25 laundry.

20 A further object of the invention is to decrease the strain on the garment, in order to avoid unnecessary wear and tear at the point of attachment of the hose supporter and the change in position of the hose supporter from stretch of the garment, when the latter is of knit goods and the strain will be so distributed that the hose is, in effect, supported from the shoulders of the wearer.

25 In the accompanying drawings is illustrated a structural embodiment of this invention in a preferred form, in which:

30 Figure 1 is a front elevation of a union suit of the athletic type having knee drawers, illustrating the improved method of attaching the garter to a union suit and of distributing the strain; Fig. 2 is a side elevation of a union suit on a wearer showing the attached garter supporting the hose; Fig. 3 is a longitudinal section with the garter attachment in elevation taken on the line 3—3 of Fig. 2; Fig. 4 is a transverse section taken on the line 4—4 of Fig. 2; Fig. 5 is a detailed plan view of a preferred form of 35 clip carried by the garter attachment; Fig. 6 is a side elevation of the same; Fig. 7 is a top elevation of Fig. 6; Fig. 8 is a front elevation of a portion of a union suit and its appendages, showing a different method of realizing my invention; Fig. 9 is a longi-

tudinal section with the garter attachment in elevation taken on the line 9—9 of Fig. 8; Fig. 10 is a view similar to Fig. 8, but illustrating a further modification; and Fig. 11 is a longitudinal section partly in elevation on the line 11—11 of Fig. 10.

60 Referring more particularly to the drawing, a union suit of the athletic type is indicated by the reference numeral 1, provided with a waist-band 2 of webbing, which unites the shirt portion 3 and the drawers portion 4. Secured to the side of the drawers leg 5 is a tape 6 extending longitudinally along the leg and with its lower end preferably near or adjacent to the lower 65 end of the garment, with rows of transverse stitching spaced at intervals to form a plurality of superimposed loops 7, indicating a similar number of predetermined points at which the hose supporter may be applied, 70 the manner of application of which will be hereinafter described. To lessen the strain at the loop in use and prevent tearing of the garment, particularly when of knit fabric, it is desirable that a reinforcement be 75 provided. This may be accomplished by 80 any suitable reinforcement, but preferably a flat reinforcing member 8 formed of substantially inextensible material such as tape is employed. The tape 8 is stitched to the 85 inner side of the garment directly beneath the tape 6, and preferably extends longitudinally along the garment to the top edge of the waist-band 2, so that the strain is distributed equally along the garment, and, the 90 upper extremity of the reinforcing member 90 being above the waist-line of the wearer, the hose is, in effect, supported from the shoulder, so that an exceedingly secure support and fixed position of the hose 95 supporter are obtained. This method of reinforcement is particularly desirable when the garment is of knit fabric, because the elastic quality and liability to tear of the material does not afford the proper support 100 for the hose. It will be noted, however, that it is not desired to limit the application of the invention, considered broadly, to a union suit, of knit fabric, as it will be found useful also in suits of other fabrics. 105

110 Referring now to the hose supporter, it will be found preferable to use the general type indicated at 9, having at its lower extremity a form of clip 10 for holding the hose. Means for adjusting the supporter is

provided by the sliding buckle 11, although this is not essential, because of the adjustment afforded at the point of application to the garment. The preferred form of clip 5 used for securing the supporter to any one of the loops 7 on the garment can best be understood by reference to Figs. 5, to 7, inclusive. Fastened to the upper extremity of the supporter by means of the loop 12, or 10 in any convenient manner, is a spring clip 13, consisting of a loop of bent wire with overlapping ends 14 offset slightly from the plane of the clip. As shown, the clip has the general outline of a trapezoid with the 15 longer of the two parallel sides extending through the loop, although the shape of the clip is immaterial. For convenience in separating the sides or slipping the clip over the loop, the extremities of the ends 14 are bent 20 slightly outward as at 15.

From the foregoing, the operation of my improved supporter will be readily understood. Having selected the proper loop on the garment, the garter is applied simply by 25 passing the tape between the separated ends of the clip. The clip and the depending garter then hang from the garment as shown in Figs. 1 and 2. There is thus provided a 30 positive locking of the supporter to the garment in any one of the positions defined by the series of superimposed loops. In this way, adjustment to different heights on the garment is secured. It will be understood, however, that the plurality of loops 35 or other adjustment is not essential to the invention.

In Figs. 8 and 9 is illustrated a modification. The tape 16 is secured to the garment in the same manner as the tape 6 in Fig. 1, 40 to form the loops. In this form, however, each loop is provided with a buttonhole 17, for the reception of the button 18 carried at the end of the garter clip 19. The operation of this form will be obvious, so that no 45 detailed description is deemed necessary here.

Figs. 10 and 11 show a further modification in which the loops are formed by folding a piece of tape and stitching the ends to the garment, as at 20. The hanging loop portion is provided with a buttonhole 21, to 50 receive the T-shaped end 22 of the clip 23. These loops 20 are shown as formed of separate pieces of tape, but they may be formed otherwise.

It will be understood that the invention 55 is not to be limited to the specific construction and arrangement of parts shown and described, but many modifications may be made within the invention as defined by the claims.

What is claimed is:—

1. A union suit having a hose supporting member secured to the lower portion of the drawers and adapted for the attachment of a hose supporter, and a reinforcing member 65 secured throughout its length to said suit and extending in the line of strain from the lower portion of the drawers to a point above the waist line and sustaining the strain on said hose supporting member, 70 whereby the hose are supported from the shoulders of the wearer.

2. A union suit having a flat tape secured to the lower portion of the drawers and adapted to receive a hose supporter, and a 75 flat substantially inextensible reinforcing tape secured throughout its length to the inside of said garment and extending in the line of strain from the lower portion of the drawers to a point above the waist line and 80 sustaining the strain on said first mentioned tape, whereby the hose are supported from the shoulders of the wearer.

In testimony whereof, I have hereunto set my hand, in the presence of two subscribing 85 witnesses.

KIRK H. WHITE.
